US0D1095490S

(12) **United States Design Patent** (10) **Patent No.:** **US D1,095,490 S**
Chen (45) **Date of Patent:** **** Sep. 30, 2025**

(54) **WIRELESS HEADSET WITH MICROPHONE AND CHARGE DOCK**

(71) Applicant: **Shenzhen aojiesheng technology co., ltd**, Shenzhen (CN)

(72) Inventor: **Qianxian Chen**, Shenzhen (CN)

(73) Assignee: **Shenzhen aojiesheng technology co., ltd**, Shenzhen (CN)

(**) Term: **15 Years**

(21) Appl. No.: **29/923,031**

(22) Filed: **Dec. 27, 2023**

(51) LOC (15) Cl. **14-01**

(52) U.S. Cl.

USPC **D14/206**; D14/226; D14/224

(58) **Field of Classification Search**

USPC ... D14/206, 226, 224, 205, 224.1, 142, 138, D14/434, 432, 155, 253, 25, 1, 149, D14/435.1; D13/108; 381/374 CPC H04R 25/00; H04R 25/02; H04R 3/00; H04R 1/10; H04R 1/1066; H04R 19/04; H04R 1/1025; H04R 1/1008; H04R 1/105; H02J 7/0042; G06F 1/16; H04M 1/04

(57) **CLAIM**

The ornamental design for a wireless headset with microphone and charge dock, as shown and described.

DESCRIPTION

FIG. 1 is a front perspective view of a wireless headset with microphone and charge dock, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of the wireless headset, of the wireless headset with microphone and charge dock, shown separately for ease of illustration.

1 Claim, 8 Drawing Sheets
